COUNTER

Clarence L. Hobart, Riverside, and Perle E. Tarlton, Los Angeles, Calif., assignors to Electric Fruit Marking Co., Los Angeles, Calif., a corporation of California

Application May 7, 1931. Serial No. 535,674

3 Claims. (Cl. 235—91)

Our invention relates to a counter in which a shift may be made from one set of enumerating devices to another set, the first set remaining stationary at their last reading so that an entry may be made in a book or other form of the reading of the stationary enumerators while the other enumerators are in operation.

Our invention is illustrated as being used in connection with grading and distributing fruit or other similar produce in the packing houses, in which houses it is the custom for one consignment from a grower to be handled and the articles graded and otherwise sorted and each grade enumerated. It has been the prior practice when one batch or consignment of fruit or other similar produce has been run through the grading or sorting machines for the machines to be stopped or else no new batch or consignment run through or handled until the foreman or other person can make a note of the reading of all of the enumerators. This necessitates a considerable delay as a tally must be made of all the different grades, each grade having a separate enumerator, and under this practice the machinery cannot be used continuously as it is necessary to clear off one batch or consignment completely before the other goes through the enumerators.

We have, therefore, constructed an operating device for enumerators particularly adapted for enumerating fruit or other similar produce in which one set of enumerators may be stationary while another set is being operated, and by a remote control device the operating mechanism may be shifted to reverse the action of the enumerators causing the one which was stationary to operate and the former operating one to be stationary. This gives the foreman or other person making the tally sufficient time to make this at leisure and, hence, there is less likelihood of the tally at the enumerations being incorrect.

Another object and feature of our invention is that the shift from one enumerator to another may be made without stopping the grading machine or without stopping fruit or other produce passing through the tripping or similar device which is used to actuate the enumerators.

Our invention is illustrated in connection with the accompanying drawings, in which:

Fig. 1 illustrates in plan a partial section of a grading and sizing machine suitable for handling citrus fruit with our enumerators and the operating mechanism therefor installed;

Fig. 2 is a transverse section on the line 2—2 of Fig. 1 in the direction of the arrows;

Fig. 3 is a plan taken in the direction of the arrow 3 of Fig. 2;

Fig. 4 is a detailed section on the line 4—4 of Fig. 2 in the direction of the arrows through the trigger or tripper device actuated by the passing fruit or other articles;

Fig. 5 is an enlarged view showing the mounting of the enumerating devices and the arrangement for alternately operating these;

Fig. 6 is a section on the line 6—6 of Fig. 5 in the direction of the arrows;

Fig. 7 is a detail section on the line 7—7 of Fig. 5 in the direction of the arrows.

In the illustration an infeeding belt 11 is illustrated as discharging fruit on the longitudinally positioned grading rollers 12, these being continually rotating and on account of their tapering spacing discharging differently sized fruit at different places longitudinally of the grading machine. The fruit or other produce is discharged on a wide feeding belt 13, this operating over an inclined table 14, and the different grades of fruit are carried between a lower separating barrier 15 and an upper separating barrier 16, there being a channel 17 for the passage of the fruit. Each channel discharges into a compartment 18 between adjustable partitions 19, these partitions being arranged to force the fruit off the edge of the belt into a series of bins 20. These are features which are common to a number of different types of grading machines.

The particular trigger mechanism employs a vertical stem 21 which is adjustably supported on a horizontal beam 22. There are a series of these beams, the beams having usually a longitudinal board 23 and a belt 24 operating thereover to receive the culs. The stem 21 has at the bottom an angular bracket 25. This has a horizontal section 26 and a vertical section 27, the vertical section being connected to the lower separating barriers 15, these, preferably, being formed of wood. A trigger device 28 is formed angular and has an upper section 29 which is connected by a pivot 30 to the horizontal section 26 and has a depending section 31 with a roller 32 mounted thereon. This roller is provided with a ratchet 33 engaging a spring pawl 34 preventing reverse rotation of the roller but allowing the roller to rotate in the direction of fruit passing thereunder. A tension spring 35 is coiled on the pivot 30 and is under tension to thrust the end 31 downwardly into the path of fruit.

fruit being carried through the channel 17 by the moving belt 13. When the fruit engages the roller it lifts the trigger and the fruit passes underneath.

5 An actuating device comprises an adjustable arm 36 mounted on a bolt 37, such bolt passing through a bracket 38 on the end 29 of the trigger. This arm is held in place by a resilient pressure using a spring 39 coiled on the bolt 10 and bearing against a washer, which latter presses against the arm 36. This arm 36 has a finger 40 at its upper end and such finger fits in the yoke end 41 of a bell crank 42, this bell crank being pivoted on the top of the stud 43 15 extending upwardly from the bracket 25. The opposite end 44 of the bell crank has a clamping block 45 connected thereto by a pivot 46, there being a series of holes to adjust the position of the pivot, and this block has a perforation therethrough, through which extends an 20 actuating link 47, the link being adjustably connected in the block 45 by such block having a set screw 48 to clamp the link.

The mounting for the enumerators utilizes a 25 channel-shaped bar 49 which is attached to the outer end of the beams 22, there being one for each enumerating trigger. This bar has a sloping plate 50 at its outer end on which is mounted an upper and a lower enumerator 51 and 30 52. These enumerators are of standard construction each having an actuating arm 53 and 54 connected thereto, the oscillation of such arm through a definite arc causing the enumerator to be operated. Each complete oscillation of 35 the arc operates the enumerator one unit.

Our shifting construction employs a link 55 which has its lower end 56 pivotally connected to the outer end of the arm 54 of the lower enumerator and has a sliding pivot connection 40 57 with the lower end of the upper arm 53, the link having a longitudinal slot 58 to allow free sliding of the pivot 57. The long link 47 extending from the trigger has a swivel attachment at 59 to the link 55.

45 The remote control mechanism at will shifting from an upper to a lower enumerator and vice versa comprises a longitudinal control shaft 60. This shaft is journaled at 61 in all of the bars 49 adjacent the sloping face plate 50 and 50 extends from one end of the machine to the other across all of the bins to all of the enumerators. Fixedly secured to the shaft 60 for each of the enumerators there is a clamping hub 62, this hub being attached to the shaft by set 55 screws 63. The hub has a flat spring 64, which spring fits in a slot 65 in a cylindrical lug 66 on a lower end 67 of a bell crank 68. This bell crank has a hub 69 freely rotatable on the shaft 60. The upper arm 70 of the bell crank has a cylindrical lug 71 at its extremity. The lug 71 is 60 positioned to contact with the arm 53 of the upper counter, and the lug 66 of the lower arm of the bell crank to engage the arm 54 of the lower counter 52. It will thus be apparent, as 65 illustrated in Figs. 2 and 5 in full lines, that

when the upper lug engages the upper arm of the enumerator such enumerator cannot be operated but the lower lug 66 is retracted and the arm 54 of the lower enumerator may be oscillated. Hence, as the trigger operates, reciprocating the 80 link 47, the link 55 swings on the pivot 57 and the arm 54 is oscillated.

When the shaft 60 is oscillated a predetermined amount the lug 66 is advanced to engage the arm 54 into the dotted line position of Fig. 5 85 and the lug 71 is retracted. This allows an oscillating movement for the arm 53 of the upper enumerator. The link 55 moved by the reciprocating motion of the link 47 then oscillates on the pivot 56.

In order to form stops for the motion of the bell crank there are stop lugs 72 and 73 formed on the inclined plate 50. However, these are not, in reality, necessary, as it is usual to provide a fixed arc of oscillation of the shaft 60; and the means for oscillating this shaft comprises a resilient arm 74 which is secured by a hub 75 to one end of the shaft 60. This arm operates on a face 76 on a fixed bracket 77, such bracket being attached to one of the beams 22. 100 The face 76 has notches 78 which form a limit to the movement of the lever, the swing of the lever being sufficient to shift the bell crank from one position to another to stop one enumerator and allow operation of the other.

Various changes may be made in the details of construction without departing from the spirit or scope of the invention as defined by the appended claims.

We claim:

1. A counter having a pair of enumerators, each having an oscillating arm, a control means comprising a bell crank, means to actuate said bell crank to render one arm inoperative and to permit operation of the other arm, and an actuating device to actuate whichever arm of the enumerator is free to operate.

2. A counter having a pair of enumerators, each having an oscillating arm, a control device comprising a bell crank, means to actuate said bell crank to cause one of the arms of the bell crank to engage one of the arms of an enumerator and to retain such enumerator stationary but to permit operation of the other enumerator, a link connecting the two enumerator arms, and a common actuating means for said link.

3. A counter having a pair of enumerators each having an oscillating arm, a link pivotally connected to one arm and having a pivot and slot connection to the other arm, and a reciprocating actuating means connected to the link, a pivotally mounted bell crank having two arms, each of said arms being adapted alternately to engage one of the arms of the enumerator whereby one arm may be held stationary while the other is permitted to operate, the reciprocation of the actuating means operating whichever arm is free to oscillate.
